Fig. 5

The characteristic features of my design reside in the complementary depressions in each half of the container in the configuration and arrangement shown.

I claim:

The ornamental design for a shipping container for medical specimens, substantially as shown and described.
